CLAIM

The ornamental design for a bottle for bird nourishment system, as shown and described.

DESCRIPTION

FIG. 1 is an isometric view of a bottle for bird nourishment system, shown with the cap component removed, in accordance with our new design;

FIG. 2 is a bottom perspective view thereof;

FIG. 3 is a first side view thereof;

FIG. 4 is an opposite side view thereof;

FIG. 5 is a front view thereof;

FIG. 6 is a back view thereof;

FIG. 7 is a top view thereof;

FIG. 8 is a bottom view thereof;

FIG. 9 is an isometric view of the bottle for bird nourishment system, shown engaged with the cap component;

FIG. 10 is a bottom perspective view thereof;

FIG. 11 is a first side view thereof;

FIG. 12 is an opposite side view thereof;

FIG. 13 is a front view thereof;

FIG. 14 is a back view thereof;

FIG. 15 is a top view thereof; and,

FIG. 16 is a bottom view thereof.

The portions shown in broken lines are environment only and form no part of the claimed design.
